WELL LID

Leslie Combs, Kingston, Ark.

Application October 3, 1934, Serial No. 746,735

1 Claim. (Cl. 166—15)

This invention relates to a well lid and has for the primary object the provision of a device of this character which will provide a closure for an open well to prevent entrance of foreign matter thereto and which forms a support for the water obtaining bucket when not in use, the latter acting to retain the device in well closing position so that when removed for use, the device immediately assumes well uncovering position and is so constructed as to permit free or unobstructed use of the bucket to obtain water from the well in the usual manner.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a front elevation, partly in section, illustrating a well lid constructed in accordance with my invention.

Figure 2 is a side elevation illustrating the same.

Figure 3 is a sectional view taken on the line 3—3 of Figure 1.

Referring in detail to the drawing, the numeral 1 indicates a vertically arranged supporting structure composed of intermediate and side members 2 and 3. The side members parallel one another and are integrally connected at their upper end by an arcuately curved and horizontally arranged head 4 to which the upper end of the intermediate member is secured. The lower ends of said members are secured to a split band or clamp 5 adapted to encircle the upper end of a well casing 6 and be secured thereto by a bolt or like fastener 7 extending through apertures

in the offset ends 8 of the split band or clamp. The band or clamp has formed thereon a hinged barrel 9 engaged by spaced hinge barrels 10 carried by a lid 11. A hinged pintle or shaft 12 extends through the barrels for hingedly connecting the lid to the clamp. The pintle or shaft 12 has one end offset laterally and secured to the lid and secured to said shaft or pintle adjacent to said opposite end is a crank arm 13 to which is pivoted a link 14 and the latter is in turn pivoted to a lever 15 pivoted to the upper portion of the supporting structure 1. One end of the lever 15 is offset to form a hook 16 on which may be suspended a well bucket 17 when not in use. The weight of the bucket on the lever retains the lid in well closing position and connected to the lever 15 and to the supporting structure is a coil spring 18 acting to move the lid into well opening position on the removal of the bucket from the hook 16. The specific construction of the supporting structure 1 will permit free vertical movement of the bucket in either direction so that water may be obtained from the well in the usual manner of raising and lowering the bucket.

Having described the invention, I claim:

A well lid comprising a vertically arranged supporting structure, means for mounting said structure to a well casing, a lid hinged to said means for opening and closing the well, a lever pivoted to the upper end of the supporting structure and connected to the lid and having one end bent to form a hook to be engaged by a well bucket when not in use for positioning the lid in well closing position, and a spring between the lever and the supporting structure to automatically effect opening of the well on the removal of the bucket from the hook.

LESLIE COMBS.
